UNITED STATES PATENT OFFICE.

HARVEY G. EGGLESTON, OF IONIA, MICHIGAN.

ADJUSTABLE DEAD-COLLAR FOR WOODWORKING-SHAPERS.

1,032,128.

Specification of Letters Patent.

Patented July 9, 1912.

Application filed November 17, 1911. Serial No. 660,867.

To all whom it may concern:

Be it known that I, HARVEY G. EGGLESTON, a citizen of the United States of America, residing at Ionia, in the county of 5 Ionia and State of Michigan, have invented certain new and useful Improvements in Adjustable Dead-Collars for Woodworking-Shapers; and I do hereby declare the following to be a full, clear, and exact description of the invention, such as will enable others skilled in the art to which it appertains to make and use the same.

My invention relates to improvements in adjustable collars for wood working shapers 15 and its object is to provide a device which may be easily attached to the ordinary wood working shaper without any alteration of the said shaper, to provide a device simple in construction and effective in operation 20 and to provide the device with various other new and useful features hereinafter more fully described and particularly pointed out in the claim.

It is customary in shaping irregular outlined pieces of material on a wood working shaper, to provide a pattern the edge of 25 which conforms to the desired outline of the material to be shaped and to provide means for clamping the material to the pattern and 30 it has been customary to run the edge of the pattern in contact with the running collars on the shaper spindle to guide the material against the knives. This is objectionable for that the friction of the pattern against 35 the running collar soon destroys the pattern and also retards the rotation of the spindle. In a good many cases the rotating collar is not fixed absolutely true on the spindle and in rotating against the pattern will vibrate 40 the same thus producing rough work.

It is the object of this invention to overcome these objections by providing stationary collars to surround the rotating collars on the spindle against which the edge of the 45 pattern is moved to guide the work and means for holding and adjusting these non-rotating collars as will more fully appear by reference to the accompanying drawings, in which:—

50 Figure 1 is a perspective view of a portion of the shaper table showing my newly invented dead collar device in operative

position and illustrating one form of pattern: Fig. 2 is a plan view of the device; Fig. 3 is a side elevation of the same; and 55 Fig. 4 an end view.

Like numbers refer to like parts in all of the figures.

1 represents the shaper spindle.

2 is the pattern in which the work to be 60 shaped is clamped the edge 2^a of which has the desired form of the work to be shaped and engages the stationary collars to guide the work.

3 is a post rigidly supported in one end of 65 a bed plate 4 secured to the table of the shaper, cap screws 8 being shown for that purpose. To the other end of this bed plate is secured a lower stationary collar 5 which surrounds the spindle below the knives and 70 close to the table of the shaper.

6 is an arm arranged parallel with the bed plate carried by the post 3 and vertically adjustable thereon, to space apart the collars to conform to the various widths of 75 knives that may be used on the spindle. This arm 6 is preferably splined to the post as at 9 to maintain it parallel with the bed plate 4 and has a collar 7 fixed to its outer end directly above the collar 5. These two 80 collars are non-rotative and concentric with the shaper spindle which rotates freely within them. A set screw 10 maintains the upper arm in adjustment on the post.

For work of considerable width it is 85 sometimes desirable to use a double pattern and both collars as illustrated in the drawings but obviously either one or the other of the collars may be used if preferred with a single pattern.

The operation of the machine is substantially the same as an ordinary shaper except that the collar is moved in contact with the non-rotating collars 5 and 7 and thus avoids the objections mentioned.

By the use of my device the patterns are not injured in any way and there is no frictional resistance to the rotation of the spindle. The user is also able to work much more rapidly as the pattern edge always engages a rigid smooth surface and smooth work will always result without any particular skill or painstaking on the part of the operator.

What I claim is:—

In combination with a wood working shaper, a bed plate secured to the table of the shaper, a post fixed in one end of the bed plate, a collar fixed on the other end of the bed plate and concentric with the spindle of the shaper, an arm above the bed plate vertically adjustable on the post and splined thereto and a collar fixed on the outer end

of the arm and concentric with the axis of 10 the shaper spindle.

In testimony whereof I affix my signature in presence of two witnesses.

HARVEY G. EGGLESTON.
